UNITED STATES PATENT OFFICE.

SETH A. CRONE, OF EAST ORANGE, NEW JERSEY.

RAILWAY-BRAKE.

1,272,779.

Specification of Letters Patent. Patented July 16, 1918.

Application filed September 22, 1917. Serial No. 192,663.

To all whom it may concern:

Be it known that I, SETH A. CRONE, a citizen of the United States, and a resident of East Orange, in the county of Essex and

5 State of New Jersey, have invented certain new and useful Improvements in Railway-Brakes, of which the following is a specification.

The invention pertains more particularly 10 to brake-heads and hangers therefor, and the object of the invention is to prevent the separation of the head from the hanger when, due to any cause, a key holding a brake-shoe to its head becomes separated 15 from the head. It is sometimes the case that a workman will remove the key to use for some purpose other than its intended duty and forget to replace the key in the brake-head, and in such instances, under 20 standard constructions of brake-heads, the head is entirely likely to slip from the hanger and the end of the beam with the head on it may then fall to the track. It has been found that due to various causes the keys 25 connecting brake-shoes with brake-heads become separated from the structure, and the object of my invention is to avoid the consequences which would naturally follow the slipping of the brake-head from its hanger 30 due to the absence of the key.

In carrying out my invention I so construct and connect the lower end of the usual brake-hanger and brake-head, that the hanger will retain the brake-head even 35 though the usual key be absent from such head, and I have sought to carry out my invention by means not adding materially to the weight or expense of the head or hanger.

40 The invention will be fully understood from the detailed description hereinafter presented, reference being had to the accompanying drawings, in which:

Figure 1 is a side elevation of a brake- 45 head and its hanger constructed in accordance with and embodying my invention;

Fig. 2 is a face view of the same, and

Fig. 3 is a side elevation, partly broken away, of a head and hanger embodying my 50 invention, the hanger being shown as engaged in the upper recess of the head instead of in the lower substantially central recess.

In the drawings, 10 designates the brake-

head and 11 the hanger by which the head 55 and the adjacent end of the beam, not shown, are suspended in a customary manner.

The hanger 11 may be of any usual or suitable type, and the only addition I make 60 to the hanger is to equip the lower wrist of the same with a pin or downwardly extending lug or projection 12. I prefer to employ an ordinary straight pin for the member 12 and to secure the upper end of the 65 same, by a shrinking operation, in a socket formed in the wrist of the hanger.

The head 10 is, in its main features, of standard construction, there being the customary socket 13 for the adjoining ends of 70 the tension and compression members of the brake-beam, not shown, lugs 14, 15, 16 and 17, to receive the brake-shoe and its securing key, not shown, a central transverse recess 18 to receive the lower wrist of the 75 hanger when it is desired to suspend the head from that point, and an upper transverse recess 19 to receive the lower wrist of the hanger when it is desired to suspend the head from a point above the brake beam. 80

The new features presented in the head 10 reside in the provision of two arcuate slots 20, 21 in the body of the head at the respective recesses 18, 19 to receive the pin or projection 12, the slot 20 receiving said 85 pin or projection when the hanger is in the recess 18 of the head and the slot 21 receiving said pin or projection when the hanger is in the recess 19 of the head. The head may be formed with either the slot 20 or 90 the slot 21, but will preferably be constructed with both of said slots and both recesses 18, 19 so that the head and hanger may be connected either at the recess 18 or the recess 19, as may be preferred. The slot 20 is 95 formed in the portion 22 constituting the lower wall of the recess 18, and below said portion 22 the casting is transversely slotted, as at 23, thereby leaving an opening 100 into which the lower end of the pin or projection 12 may extend. The front end of the slot 20 is closed by a portion 24 of the head, and this portion 24 serves as a stop to prevent the lower end of the pin or projection 12 from swinging outwardly from the 105 slot 20. The upper end of the slot 20 is also closed, as denoted at 25.

In applying the hanger 11 to the recess 18

of the head 10, I turn said hanger downwardly into a position almost at right angles to the face of the head and insert the end of the pin or projection 12 into the slot 20, 5 gradually working the same therein and turning the hanger upwardly so that its lower wrist becomes lodged within the recess 18 and the pin or projection 12 becomes confined within the slot 20. When the lower 10 wrist of the hanger 11 is within the recess 18 and the pin or projection 12 is confined within the slot 20, said head and hanger may have their usual swinging movements, but the pin will prevent the head from leaving the hanger, even though the shoe-secur- 15 ing-key may be absent, and the accomplishment of this purpose is the chief object of my invention.

The slot 21 corresponds with the slot 20, 20 except that it is located about the lower portion of the recess 19, and said slot 21 is closed at its lower front end by a portion of the head 26 which, like the portion 24 hereinbefore referred to, serves as a stop to 25 prevent the escape of the pin or projection 12 from the slot. The upper end of the slot 21 is closed, as at 27. The slot 21 will be made use of when the lower wrist of the hanger is to be engaged in the recess 19 of 30 the head, and this arrangement of the head and hanger is illustrated in Fig. 3. There is no difference in construction between what is represented in Fig. 1 and that which is shown in Fig. 3, the difference between 35 the two illustrations being that in Fig. 1 the hanger is shown as engaged in the recess 18, while in Fig. 3 the hanger is shown as engaged in the recess 19. The hanger may be applied to the recess 19 and slot 21 40 in the same manner that I have hereinbefore described with reference to the application of the hanger to the recess 18 and slot 20.

When the head and hanger are construct- 45 ed and connected together in the manner hereinbefore described, the head will remain connected with the hanger even though the brake-shoe and brake-shoe-key should become broken or detached or omitted from 50 the head, and hence in the absence of the shoe and key the head will remain suspended by the hanger and not be permitted, with its end of the brake-beam, to fall down to the roadbed. The head and hanger are, 55 by means of my invention, detachably connected together, and the presence of my invention does not materially increase the cost or weight of either the head or hanger.

I do not limit my invention to the presence 60 in the head 10 of both of the slots 20, 21, but I greatly prefer to equip the head with both of said slots and both recesses 18, 19, so that the head may be connected to the hanger at either the recess 18 or recess 19,

as may be preferred, or as the circumstances 65 might render expedient.

What I claim as my invention and desire to secure by Letters Patent, is:

1. A brake-head having a face adapted to receive a brake-shoe and key and provided in said face with an open recess back of the path of the key to receive the wrist of a brake-hanger, and a brake-hanger having a wrist adapted to said recess, said head being formed with a slot extending along the wall 75 of said recess and closed at its outer end, and said wrist having a projection freely confined within said slot and adapted to prevent the unintended escape of the head from the hanger. 80

2. A brake-head having a face adapted to receive a brake-shoe and key and provided in said face with an open recess back of the path of the key to receive the wrist of a brake-hanger, and a brake-hanger having a wrist adapted to said recess, said head being formed with an arcuate slot extending along the lower and rear wall of said recess and closed at its outer end, and said wrist having a projection freely confined within 90 said slot and adapted to prevent the unintended escape of the head from the hanger. 95

3. A brake-head having a face adapted to receive a brake-shoe and key and provided in said face with upper and lower open recesses back of the path of the key to receive, in either recess, the wrist of a brake-hanger, and a brake-hanger having a wrist adapted to either of said recesses, said head being formed with slots extending along the walls 100 of said recesses and closed at their outer ends, and said wrist having a projection to be freely confined within either of said slots and adapted to prevent the unintended escape of the head from the hanger. 105

4. A brake-head having a face adapted to receive a brake-shoe and key and provided in said face with upper and lower open recesses back of the path of the key to receive, in either recess, the wrist of a brake-hanger, and a brake-hanger having a wrist adapted to either of said recesses, said head being formed with arcuate slots extending along the lower and rear walls of said recesses and closed at their outer ends, and said wrist having a projection to be freely confined within either of said slots and adapted to prevent the unintended escape of the head from the hanger. 110

5. A brake-head having a face adapted to receive a brake-shoe and key and provided in said face with an open recess back of the path of the key to receive the wrist of a brake-hanger, and a brake-hanger having a wrist adapted to said recess, said head being formed with a slot at said recess, and said wrist having rigidly secured thereto a projection confined within said slot and 115 120 125

adapted to prevent the unintended escape of
the head from the hanger, and said recess,
wrist, projection and slot being so related
that the wrist carrying the projection may,
5 when in one position, enter said recess and
position said projection within said slot.

Signed at New York city, in the county of

New York and State of New York, this 19th
day of September A. D. 1917.

SETH A. CRONE.
